LAPPING MACHINE

Walter F. Egger, Rocky River, Ohio, assignor to
 Albert P. Schraner, Shaker Heights, Ohio, doing
 business as A. P. Schraner & Co.

Application November 11, 1943, Serial No. 509,850

12 Claims. (Cl. 51—73.1)

This invention relates as indicated to lapping machines and more especially to machines of the character which are designed to lap or polish the cylindrical surfaces of rotatable workpieces such as crankshafts and the like, i. e. those portions of the crankshaft on which the main and connecting rod bearing surfaces are provided.

It is a more specific object of my invention to provide an apparatus of the character described which will effectively lap or polish those portions of said bearing surfaces which extend at right angles to the axis of the workpiece, that is, they extend in a plane substantially normal to the axis about which the shaft is rotated.

Lapping machines of this character generally employ an abrasive coated ribbon, an intermediate portion of which is moved into engagement with the area being operated upon.

It is a further and more specific object of my invention to provide an improved means for supporting and sustaining such abrasive coated ribbon in the operative engagement with the work while, at the same time, guarding against damage to the work in the event such ribbon becomes de-ranged or broken.

Other and more particular objects of my invention will appear as the description proceeds.

To the accomplishment of the foregoing and related ends, said invention then comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a side elevational view partially in section of one form of apparatus embodying the principles of my invention;

Fig. 2 is a side elevational view drawn to an enlarged scale of a portion of the apparatus illustrated in Fig. 1;

Fig. 3 is a plan view of that portion of the apparatus illustrated in Fig. 2;

Fig. 4 is a transverse sectional view of the apparatus illustrated in Fig. 1, taken on a plane substantially indicated by the line 4—4;

Figs. 5 and 6 are respectively fragmentary sectional views of a portion of the apparatus as illustrated in Fig. 5 showing the several parts thereof in different positions;

Fig. 7 is a side elevational view of another form of apparatus embodying in a different environment one of the principles of my invention;

Fig. 8 is a fragmentary side elevational view of one of the work-engaging jaws of the apparatus of Fig. 7; and

Fig. 9 is a transverse sectional view of the structure illustrated in Fig. 8, taken on a plane substantially indicated by the line 9—9.

Referring now more specifically to the drawings and more especially to Fig. 1, the apparatus here illustrated, and incorporating certain of the features of my invention, is part only of a complete lapping machine such as that illustrated in my prior Patent No. 2,121,025, issued Jan. 21, 1938. Only so much of that machine as is related to the present invention has been illustrated and will be described herein. For a description of the general operation of the machine, reference may be had to my said prior patent.

In my said prior patent the bearing surfaces of the crankshaft are engaged at diametric opposite points by jaws over which are stretched ribbons of abrasive coated material, and such jaws are urged into engagement with the outer cylindrical surface of the bearing areas under the influence of a fluid actuated ram 1. The present invention is concerned with the provision of work-engaging heads which will lap or polish the shoulders or side parts of the bearing areas, i. e. those which extend in a plane normal to the axis of rotation of the crankshaft. Two identical heads are provided, each carried on the lower end of bell-crank levers 2, the upper ends of which levers are connected through toggle links 3 to the head 4 of the piston rod 5 of the jack 1. Thus, when the piston rod is elevated, the toggle linkage just described will move the heads, generally indicated at 6, into engagement with the crankshaft, and when the piston rod 5 descends, the head 6 will be moved out of engagement with the crankshaft. The construction of the heads 6 is most clearly illustrated in Figs. 2 to 6. Since these heads are identical, only one will be described, and similar reference characters will be employed to designate corresponding parts on the other head.

To a base member 7 there is secured, as by welding or otherwise, an upstanding member 8, and also a pin 9. Rotatably mounted on the pin 9 is a spool 10, carrying an abrasive coated ribbon 11. The upstanding member 8 is provided with slots 12 at opposite sides for the purpose of guiding the abrasive coated ribbon which is passed therethrough.

Likewise secured to the base 7 is an upstanding wedge-shaped part 13, the uniform cross-section 55 of which is most clearly apparent from an in-

spection of Figs. 4 to 6. The member 13 is provided with a slot on its outer vertical face into which extends the lower end of the bell-crank 2. Aligned openings extending transversely through the member 13 and the end of the arm 2 receive a pin 14 by which the member 13 is removably attached to the arm 2.

Mounted on opposite sides of the member 13 are cam members 15 and 16, the uniform cross-section of which will be apparent from Figs. 4 and 6, and the lateral configuration of which will be apparent from Fig. 2. The inner faces of the members 15 and 16 are arcuate and of a diameter slightly greater than the diameter of the bearing surface on which the apparatus is designed to operate.

The upper and lower corners of each of members 15 and 16 are provided with identical removable projections 17, each of which is provided with an opening 18 to receive the terminal portion of a cross-shaft 19. On the cross-shafts 19 are mounted rollers 20, the outer surfaces of which lie on an arc having a diameter slightly less than the arc of the inner faces of the members 15 and 16. The arc on which the rollers 20 lie should have a radius equal to the radius of the bearing surface being operated upon. The shafts 19 are secured at one end in either the member 15 or 16, and at their opposite ends slideable in the opening embracing the same, so that the members 15 and 16 may move toward and away from each other.

On the upper and lower faces of each of members 15 and 16 are projecting pins 21, and to such pins are secured the opposite ends of springs 22 biased so as to resiliently urge the members 15 and 16 toward each other against the inclined opposed faces of the central member 13.

The members 15 and 16 are provided with slots 23, the vertical dimension of which is equal to the diameter of the pin 14, with the horizontal dimension substantially greater than such diameter in order that, as viewed in Figs. 4 to 6, relative movement between the members 15 and 16 and central member 13 may occur.

Intermediately of their ends, the members 15 and 16 are provided with attached pads 24 of oil-resistant synthetic rubber. The inner face of the pads 24, i. e. those faces directed toward the cylindrical bearing surface, have a radius sufficiently greater than the radius of such bearing surfaces so that the abrasive coated ribbon passing thereover will not have contact with such cylindrical surfaces when the rollers 20 are in engagement with such cylindrical surfaces.

The function and operation of the apparatus just illustrated is briefly as follows:

With the heads mounted on the ends of the arms 2 and out of engagement with the bearing surface on the crankshaft, the piston rod 5 is elevated causing such heads through the toggle linkage, previously described, to move into engagement with the bearing surface. With the heads out of engagement with the bearing surface, the springs 22, urging the members 15 and 16 toward each other, will cause such members and associated part 13 to occupy the relationship illustrated in Fig. 5. However, when the toggle arms 2 are moved toward the bearing, they, acting through the wedge-shaped members 13, will cause the members 15 and 16 to spread apart, as illustrated in Fig. 6, until their opposite faces, i. e., those carrying the pads 24, move into engagement with the radial shoulders 25 on opposite sides of the cylindrical bearing area or crank pin.

The pads 24 will hold the abrasive coated ribbon against these radial shoulders, and during the subsequent rotation of the crankshaft, such radial shoulders, as well as the fillet joining the radial shoulders and the cylindrical surface, will be lapped and polished.

At the conclusion of the operation, the piston rod 5 will be lowered, separating the heads from the shaft, whereupon the springs will move the members 15 and 16 toward each other, and the apparatus may then be swung out of engagement with the crankshaft.

In any lapping operation, such as that just described, and such as is adapted to be performed by the apparatus of my aforementioned prior patent, some means must be provided for the purpose of preventing shifting between the abrasive coated ribbon and the lapping arm or head by which the same is moved into engagement with the work.

It has been common practice up to the time of my invention to coat the machine part which engages the back face of the abrasive ribbon with a relative coarse abrasive material so as to prevent relative movement between the ribbon and the part which forces the ribbon into engagement with the work. Heretofore, no other means has been found satisfactory for this purpose. In practice, however, these abrasive coated ribbons have a tendency to tear or become misaligned, and when this happens the part carrying the coarse abrasive comes in contact with the bearing surface to be lapped, scoring, and in many times, ruining the entire crankshaft.

The employment of oil-resistant synthetic rubber as the material for the pad 24 obviates this difficulty. I have found that commercially available synthetic rubber, sold under the name Neoprene, and other products similar thereto, is entirely satisfactory for this purpose.

This expedient of holding in place and resiliently backing up the abrasive coated ribbon may be employed in environments other than the specific embodiment of my invention thus far described.

For example, in an apparatus of the character illustrated in my said prior patent, and as illustrated in Fig. 7, the invention will be found of particular utility. In this type of lapping machine, the cylindrical surfaces of the bearing to be lapped are engaged at diametrically opposite areas by means of jaws 27, the inner faces of which are arcuate on a radius substantially equal to the radius of the cylindrical bearing surface being lapped.

In accordance with the prior practice, it has been conventional to provide on these inner faces of the blocks 27 a sheet of coarse sand paper holding the abrasive coated ribbon 28 from slipping relatively to the blocks 27 during the lapping operation. As previously indicated, should the abrasive coated ribbon 28 tear, then the coarse sand paper comes in contact with the bearing surface, many times so scoring the same as to require rejection of the entire crankshaft.

This problem I have solved by providing on the inner faces of the blocks 27 a layer 29 of synthetic rubber, and in the preferred embodiment of my invention, the resilient pad thus provided has a series of spaced grooves 30 formed therein, such grooves extending substantially parallel to the axis of relative rotation between the bearing and the blocks 27. This expedient of grooving the rubber pad is of particular importance in that it permits intermediate spaced portions of

the ribbon 28 to become wedged in the grooves, thus insuring against relative movement between the ribbon and the pad during the lapping operation.

Similarly, if the extent of the pads 24 of Fig. 2 are considerable, then they too should preferably be provided with grooves which extend transversely of the direction of relative movement between the part being lapped and the abrasive coated ribbon.

I have thus provided an improved lapping machine which accomplishes all of the objects aforesaid, and which in particular is effective to polish or lap those surfaces of crankshafts which have heretofore been finished entirely by hand.

Other modes of applying the principle of the invention may be employed, change being made as regards the details described, provided the features stated in any of the following claims or the equivalent of such be employed.

I therefore particularly point out and distinctly claim as my invention:

1. In apparatus for lapping a work piece of the general form of a crank shaft with crank-pin and adjoining shoulder surfaces, the combination of a carrier part, primary means on said carrier part engageable with the work in an area adjacent said shoulder surface, secondary means on said carrier engageable with said shoulder surface and movable relatively to said carrier in a direction substantially parallel to the axis of the crank-pin, and means for effecting said last named movement.

2. In apparatus for lapping a work piece of the general form of a crank shaft with crank-pin and adjoining shoulder surfaces, the combination of a carrier part, primary means on said carrier part engageable with the work in an area adjacent said shoulder surface, secondary means on said carrier engageable with said shoulder surfaces and movable relatively to said carrier in a direction substantially parallel to the axis of the crank-pin, means intermediately of said primary and secondary means whereby pressure of the former against said work effects said last named movement.

3. In apparatus for lapping a work piece of the general form of a crank-shaft with crank-pin and adjoining shoulder surfaces, the combination of a carrier part, primary means on said carrier part engageable with the work in an area adjacent said shoulder surface and responsive to such engagement movable relatively to said carrier in a plane substantially normal to the axis of the crank-pin, secondary means on said carrier engageable with said shoulder surface and movable relatively to said carrier in a direction substantially parallel to the axis of the crank-pin, means intermediately of said primary and secondary means whereby relative movement between the former and said carrier effects relative movement between said secondary means and said carrier to cause said secondary means to move into engagement with said shoulder surfaces.

4. In apparatus for lapping a work piece of the general form of a crank-shaft with crank-pin and adjoining shoulder surfaces, the combination of a carrier part, primary means on said carrier part engageable with the work in an area adjacent said shoulder surface and responsive to such engagement movable relatively to said carrier in a plane substantially normal to the axis of the crank-pin, secondary means on said carrier engageable with said shoulder surface and movable relatively to said carrier in a direction substan-

tially parallel to the axis of the crank-pin, means intermediately of said primary and secondary means whereby relative movement between the former and said carrier effects relative movement between said secondary means and said carrier to cause said secondary means to move into engagement with said shoulder surface, and work engaging pads of resilient material on those faces of said secondary means which are opposed to said shoulder surfaces, said pads provided with grooves extending across the face thereof in a direction substantially parallel to the axis of the crank-pin.

5. In apparatus for lapping spaced opposed shoulder surfaces on a rotatable work piece of the general form of shoulder surfaces adjacent a crank-piece, the combination of a carrier part, primary means on said carrier part engageable with the work in an area intermediately of said shoulder surfaces, secondary means on said carrier engageable with said shoulder surfaces and movable relatively to said carrier in a direction substantially parallel to the axis of the crank-pin, and means for effecting said last named movement.

6. In apparatus for lapping spaced opposed shoulder surfaces on a rotatable work piece of the general form of shoulder surfaces adjacent a crank-piece, the combination of a carrier part, primary means on said carrier part engageable with the work in an area intermediately of said shoulder surfaces, secondary means on said carrier engageable with said shoulder surfaces and movable relatively to said carrier in a direction substantially parallel to the axis of the crank-pin, means intermediately of said primary and secondary means whereby pressure of the former against said work effects said last named movement.

7. In apparatus for lapping spaced opposed shoulder surfaces on a rotatable work piece of the general form of shoulder surfaces adjacent a crank piece, the combination of a carrier part, primary means on said carrier part engageable with the work in an area intermediately of said shoulder surfaces and responsive to such engagement movable relatively to said carrier in a plane substantially normal to the axis of the crank-pin, secondary means on said carrier engageable with said shoulder surfaces and movable relatively to said carrier in a direction substantially parallel to the axis of the crank-pin, means intermediately of said primary and secondary means whereby relative movement between the former and said carrier effects relative movement between said secondary means and said carrier to cause said secondary means to move into engagement with said shoulder surfaces.

8. In apparatus for lapping spaced opposed shoulder surfaces on a rotatable work piece of the general form of shoulder surfaces adjacent a crank-piece, the combination of a carrier part, primary means on said carrier part engageable with the work in an area intermediately of said shoulder surfaces and responsive to such engagement movable relatively to said carrier in a plane substantially normal to the axis of the crank-pin, secondary means on said carrier engageable with said shoulder surfaces and movable relatively to said carrier in a direction substantially parallel to the axis of the crank-pin, means intermediately of said primary and secondary means whereby relative movement between the former and said carrier effects relative movement between said secondary means and said carrier

to cause said secondary means to move into engagement with said shoulder surfaces, and work engaging pads of resilient material on those faces of said secondary means which are opposed to said shoulder surfaces.

9. In apparatus for lapping spaced opposed shoulder surfaces on a rotatable work piece of the general form of shoulder surfaces adjacent a crank-piece, the combination of a carrier part, primary means on said carrier part engageable with the work in an area intermediately of said shoulder surfaces and responsive to such engagement movable relatively to said carrier in a plane substantially normal to the axis of the crank-pin, secondary means on said carrier engageable with said shoulder surfaces and movable relatively to said carrier in a direction substantially parallel to the axis of the crank-pin, means intermediately of said primary and secondary means whereby relative movement between the former and said carrier effects relative movement between said secondary means and said carrier to cause said secondary means to move into engagement with said shoulder surfaces, and work engaging pads of resilient material on those faces of said secondary means which are opposed to said shoulder surfaces, said pads provided with grooves extending across the face thereof in a direction substantially parallel to the axis of the crank-pin.

10. The combination with a lapping element provided with an arcuate pillow adapted to maintain an intermediate portion of an abrasive coated ribbon into engagement with a substantially cylindrical surface on a rotating work piece, of a pad of oil-resistant synthetic rubber substitute on said pillow arranged to engage the back face of ribbon.

11. The combination with a lapping element provided with an arcuate pillow adapted to maintain an intermediate portion of an abrasive coated ribbon into engagement with a substantially cylindrical surface on a rotating work piece, of a pad of oil-resistant synthetic rubber substitute on said pillow arranged to engage the back face of ribbon, said pad provided with grooves extending across the ribbon-engaging face thereof in a direction angularly related to the plane of relative rotation between said pillow and the work piece.

12. In apparatus for lapping a work piece of general form of a crank-shaft with crank-pin and adjoining shoulder surfaces, an arcuate pillow adapted to maintain an intermediate portion of an abrasive ribbon in engagement with a crank-pin surface, and small rollers mounted on the upper and lower corners thereof, the arc on which the rollers lie having a radius substantially equal to the radius of the crank-shaft.

WALTER F. EGGER.
